FLIER CONSTRUCTION

Michael J. McHale, Scranton, Pa.

Application March 11, 1940, Serial No. 323,419

15 Claims. (Cl. 57—116)

My invention relates to fliers of the type used with spinning machines, and more particularly to a flier block arrangement having improved means for attaching and supporting the flier wires.

5 In Patent 2,187,862, issued to me January 23, 1940, there is disclosed a flier construction having a flier wire support member in the form of a plate adapted to fit over the head portion of the flier body or block, the plates being attached 10 to the flier body by means of a cap positioned below the plate and attached thereto by spot welding.

The present invention relates to a flier of the type disclosed in the aforementioned patent and 15 particularly to an improved form of flier wire support member, together with means for attaching the support to the flier block. After considerable experimentation, I have found that the construction of my prior patent can be substantially simplified to provide improved operation 20 with economies in manufacture.

An object of my invention is to provide a flier block having improved means for attaching and supporting the flier wires thereon.

25 Another object of my invention is to provide a flier construction having means whereby the arms of the flier wires are supported in a fixed plane in the vicinity of their points of attachment to the flier block.

30 Yet another object of my invention is to provide an improved flier construction wherein the flier wires are attached to the flier block by twisting or overlapping the arms thereof, portions of the arms beyond the points of attachment being supported in a fixed plane whereby 35 undesirable flexing of the flier wires about their points of support is prevented.

Still another object of my invention is to provide an improved flier wire support having means 40 associated therewith adapted for engagement with the body of the block whereby relative movement of the support with respect to the body of the flier is prevented.

A further object of my invention is to provide 45 an improved flier arrangement consisting of but few parts, strong and sturdy in construction, and not liable to get out of order even after long and continued use.

With these and other objects in view, which 50 may be incident to my improvements, the invention consists in the parts and combinations to be hereinafter set forth and claimed, with the understanding that the several necessary elements, comprising my invention, may be varied 55 in construction, proportions and arrangement,

without departing from the spirit and scope of the appended claims.

In order to make my invention more clearly understood, I have shown in the accompanying drawings means for carrying the same into practical effect, without limiting the improvements in their useful applications to the particular constructions, which for the purpose of explanation, have been made the subject of illustration.

In the drawings:

Figure 1 is an elevational view, partly in section, showing my improved flier in operative position on a bobbin spindle.

Fig. 2 is a plan view of the flier shown in Fig. 1.

Fig. 3 is a plan view of the bottom of the flier 15 shown in Fig. 1.

Fig. 4 is an expanded view of the parts of the flier block.

Fig. 5 is a plan view of the bottom of a modified form of flier.

Fig. 6 is a sectional view along line 6—6 of Fig. 5.

Fig. 7 is an expanded perspective view of the parts of the flier block shown in Fig. 5.

Fig. 8 is a plan view of another modified form 25 of flier.

Fig. 9 is a plan view of the bottom of the flier shown in Fig. 8.

Fig. 10 is an expanded perspective view of the parts of the flier block shown in Fig. 8, and,

Fig. 11 is an expanded view of a modification 30 of the flier shown in Fig. 10.

The improved construction of the present invention comprises essentially a flier block formed with a peripheral flange and a peripheral groove 35 above and adjacent the flange, a bi-partite flier wire support member in the form of complementary sections having semi-circular shaped cut-out portions adapted to seat in the peripheral groove at opposite sides of the block. The arms, 40 defined by the cut-out portions, are adapted to overlap, that is to say, the opposite arms of the complementary sections overlap when the recessed portions are seated in the peripheral groove. The complementary sections are also 45 provided with means adapted for engagement with the peripheral flange whereby the sections are securely clamped or locked to the flier body.

Referring to the drawings, and more particularly to Figure 1, there is shown a flier arrangement associated with a bobbin 1, mounted in operative position on a suitable spindle 2, of a conventional winding machine. The bobbin is provided with a head member 3, and a centrally recessed portion 4 adapted to receive a ferrule 55

5 having an aperture 6 through which the flier foot is inserted. The flier block, designated generally by numeral 7, comprises a centrally apertured body portion 8 having a base portion 9 and a head portion 10. Between the base and head portions, there is provided a peripheral flange 11 adapted to form a seat for portions of a flier wire support member, as will be explained more fully hereinafter.

10 The flier block 7, reference being had to Fig. 4, is also provided with a peripheral groove 12 above and adjacent the flange 11, the flange being cut away at diametrically opposite points to form slots 13 in the periphery thereof. A bipartite flier wire support member, adapted to be mounted on the flier block, is formed of complementary sections, designated generally by numeral 14, each section comprising a body portion 15 having a semi-circular shaped recess 16 cut therein, the recessed portion defining arms 17 and 17'. The end of the body portion opposite the recess is turned back upon itself and crimped to form slots or grooves 18 adapted to receive the arms 19, of the flier wires, as shown in Fig. 2.

25 It will be noted that the ends 20 of the turned over portion of the body in which slots 18 are formed are bent downwardly in overhanging relationship with the body portion of the plate so that the wires are prevented from accidental displacement out of the slots. Each section of the flier wire support member is also provided with a prong or other projection 21 adapted to seat in one of the slots 13 formed in the peripheral flange 11 of the flier wire. The purpose of this arrangement is to prevent relative movement of the flier wire support with respect to the block, that is to say, to prevent rotative movement of the plate with respect to the block.

30 In assembling the flier, one of the members 14 is inserted in a portion of the peripheral groove 12, with prong member 21 seated in one of the slots 13. The complementary section 14 is then inserted in the groove 12 at the opposite side of the block with prong 21 seated in the corresponding slot 13, the opposite arms 17 and 17' overlapping at the sides of the block, as more clearly shown in Fig. 2.

35 After the sections have been placed in the operative position, as above described, the overlapping portions may then be fastened together, as by spot welding, indicated generally by numeral 22. After the flier wire support plate has been attached to the flier body, the wires are mounted thereon by inserting an arm 19 of one of the wires 40 in a slot 18, the central block engaging portion 23 of the flier wire being in engagement with the upper peripheral surface of the body of the block, the opposite arm 19 of the same wire being then inserted in slot 18 on the same side of the block. The second wire is introduced in the manner above described, the wires overlapping at points 24 on opposite sides of the block.

45 By means of the construction and arrangement of the flier wire supporting plate, together with the improved flier block, the supporting plate can be easily and quickly applied to the block and after it is placed in the operative position, with the arms welded or otherwise attached at the overlapped portions, the plate is securely locked or clamped to the block so that it cannot move in any direction with respect thereto. The flier wires can be easily and quickly applied to the plate and are maintained in the desired operative position whereby undesirable flexing of

50 the flier wires about their points of support is prevented.

55 Referring to Figs. 5, 6 and 7, there is shown a modified form of flier construction wherein the plate is locked against rotative movement by means of the arrangement of the arm members, which are adapted for engagement with the peripheral surface of the flange 11. In this arrangement, the peripheral flange is formed with flat surfaces 25 on either side thereof, and arms 17 of the respective complementary sections are bent out of the normal plane of each of the base members 15 so that when the sections are inserted in the peripheral groove 12, arms 17 contact with the flat surface, as more clearly shown in Fig. 6. The complementary sections are welded together as by spot welding and the wire attaching means, namely, slots 18, are the same as those described in connection with the arrangement of Fig. 1.

60 Referring to Figs. 8, 9, and 10, there is shown another modification of the flier construction wherein the flier wire support member is attached to the block with the overlapped portions at the ends of the plate. In this arrangement, sections 26 and 27 are provided with semi-circular recessed portions adapted to fit into the peripheral groove 12 on opposite sides of the block. The ends 28 of section 26 are bent or crimped to form flier wire receiving slots with arms 29 of the section 27. It will be noted that section 27 is formed with prong members 30 adapted to contact with flat surfaces 31 formed on opposite sides of the block 7. In assembling the flier wire support, sections 26 and 27 are inserted in the groove 12, with arms 28 and 29 in overlapping relationship, prongs 30 resting against the flat surfaces 31. The overlapped portions are fastened together by means of spot welding as indicated by numeral 32, Fig. 9.

65 Referring to Fig. 11, there is shown a modification of the supporting plate arrangement disclosed in Fig. 10. In the modified form of the device, the peripheral flange 11 of the flier block 7 is formed with a slot 33 adapted to receive prong member 34 formed on section 35 of the plate. This section is provided with arms 36 adapted to engage with arms 37 formed on section 38, arms 37 overlapping the arms 36 when the sections are in seated position in the peripheral groove 12.

70 It will be noted in connection with the arrangement of the modified form of flier construction that the complementary sections are arranged to seat in the peripheral groove and that the wire receiving slots 28 are formed by crimping the free ends of the arms formed on one of the sections. As shown in Fig. 9, the under arm at the overlap is spot welded at the bottom of the plate.

75 While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

What I claim is:

76 1. A flier for spinning machines and the like comprising, a centrally apertured body member having base and head portions, a peripheral flier wire support receiving groove formed in the body member between the base and head por-

- 5 tions, a flier wire support adapted to seat in said groove comprising complementary members having recessed body portions defining arms in the vicinity of the open end of the recessed portions, the opposite arms of the respective complementary members being adapted to overlap when the recessed portions thereof are seated in the peripheral groove and means to securely clamp the flier wire support to the flier body.

10 2. A flier for spinning machines and the like comprising, a centrally apertured body member having base and head portions, a peripheral flier wire support receiving groove formed in the body member between the base and head portions, a flier wire support adapted to seat in said groove comprising complementary members having recessed body portions defining arms in the vicinity of the open end of the recessed portions, the opposite arms of the respective complementary members being adapted to overlap when the recessed portions thereof are seated in the peripheral groove, means formed on said complementary members adapted to receive the arms of the flier wires and means to securely lock the complementary members together.

15 3. A flier for spinning machines and the like comprising, a centrally apertured body member having base and head portions, a peripheral flange formed on the body portion between the base and head portions, a peripheral flier wire support receiving groove formed in the body above said flange, a flier wire support comprising complementary members having recessed body portions defining arms in the vicinity of the open end of the recessed portions, the opposite arms of the respective members being adapted to overlap when the recessed portions thereof are seated in the peripheral groove, means formed on one of the complementary members adapted for engagement with the peripheral flange whereby to prevent relative movement of the flier wire support with respect to the flier body and means to lock the complementary members together.

20 4. A flier for spinning machines and the like comprising, a centrally apertured body member having base and head portions, a peripheral flier wire support receiving groove formed in the body member between the base and head portions, a flier wire support adapted to seat in said groove comprising two complementary members, each having a body portion formed with a recess, the end of the body opposite of the recess being turned backwardly upon itself to form a slot adapted to receive the arms of a flier wire and means to lock the complementary members together with the recessed portions thereof in seated position in the peripheral groove.

25 5. A flier for spinning machines and the like comprising, a centrally apertured body member having base and head portions, a peripheral flier wire support receiving groove formed in the body member between the base and head portions, a flier wire support adapted to seat in said groove comprising two complementary members, each having a body portion formed with a recess defining arms in the vicinity of the open end of the recess, the opposite arms of the respective members being adapted to overlap when the recessed portions thereof are seated in the peripheral groove and means to securely clamp the flier wire support to the flier body.

30 6. A flier for spinning machines and the like comprising, a centrally apertured body member having base and head portions, a peripheral flier wire support receiving groove formed in the body member between the base and head portions, a flier wire support adapted to seat in said groove comprising two complementary members, each having a body portion formed with a recess defining arms in the vicinity of the open end of the recess, the opposite arms of the respective members being adapted to overlap when the recessed portions thereof are seated in the peripheral groove, means formed on said complementary members adapted to receive the arms of the flier wires and means to securely lock the complementary members together.

35 7. A flier for spinning machines and the like comprising, a centrally apertured body member having base and head portions, a peripheral flier wire support receiving groove formed in the body member between the base and head portions, a flier wire support adapted to seat in said groove comprising two complementary members, each having a body portion formed with a recess defining arms in the vicinity of the open end of the recess, the opposite arms of the respective members being adapted to overlap when the recessed portions thereof are seated in the peripheral groove, means to lock the complementary members together and means to clamp the flier wire support to the flier body.

40 8. A flier for spinning machines and the like comprising, a centrally apertured body member having base and head portions, a peripheral flange formed on the body portion between the base and head portions, a peripheral flier wire support receiving groove formed in the body above said flange, a flier wire support comprising two complementary members, each having a body portion formed with a recess defining arms in the vicinity of the open end of the recess, the opposite arms of the respective members being adapted to overlap when the recessed portions thereof are seated in the peripheral groove, the under arm of the overlap being in engagement with the peripheral flange whereby to prevent relative movement of the flier wire support with respect to the flier body member and means to lock the complementary members together.

45 9. A flier for spinning machines and the like comprising, a centrally apertured body member having base and head portions, a peripheral flange formed on the body portion between the base and head portions, a peripheral flier wire support receiving groove formed in the body above said flange, a flier wire support comprising two complementary members, each having a body portion formed with a recess defining arms in the vicinity of the open end of the recess, the opposite arms of the respective members being adapted to overlap when the recessed portions thereof are seated in the peripheral groove, the under arm of the overlap being in engagement with the peripheral flange whereby to prevent relative movement of said flier wire support with the flier body, the end of each of the body portions opposite the recess being turned backwardly upon itself to form a slot adapted to receive the arms of a flier wire and means to lock the complementary members together.

50 10. A flier for spinning machines and the like comprising, a centrally apertured body member having base and head portions, a peripheral flange formed on the body between the base and head portions, said flange having a portion of its periphery cut away to form a flat surface, a peripheral flier wire support receiving groove formed in the body of said flange, a flier wire support comprising two complementary members,

each having a body portion formed with a recess defining arms in the vicinity of the open end of the recess, the opposite arms of the respective members being adapted to overlap when the recessed portions thereof are seated in the peripheral groove, the under arm of the overlap being in engagement with the flat surface of the peripheral flange whereby to prevent relative movement of the flier wire support with respect to the flier body member and means to lock the complementary members together.

11. A flier for spinning machines and the like comprising, a centrally apertured body member having base and head portions, a peripheral flange formed on the body between the base and head portions, said flange having a portion of its periphery cut away to form a flat surface, a peripheral flier wire support receiving groove formed in the body of said flange, a flier wire support comprising two complementary members, each having a body portion formed with a recess defining arms in the vicinity of the open end of the recess, the opposite arms of the respective members being adapted to overlap when the recessed portions thereof are seated in the peripheral groove, the under arm of the overlap being in engagement with the flat surface of the peripheral flange whereby to prevent relative movement of the flier wire support with respect to the flier body, the end of each of the body portions opposite the recess being turned backwardly upon itself to form a slot adapted to receive the arms of a flier wire and means to lock the complementary members together.

12. A flier for spinning machines and the like comprising, a centrally apertured body member having base and head portions, a peripheral flange formed on the body portion between the base and head portions, said flange having slots cut therein at diametrically opposite points, a peripheral flier wire support receiving groove formed in the body above said flange, a flier wire support comprising two complementary members, each having a body portion formed with a recess defining arms in the vicinity of the open end of the recess and a prong member formed by striking out a portion of the body adjacent the recess, the opposite arms of the respective members being adapted to overlap when the recessed portions thereof are seated in the peripheral groove, said prong members seating in the slots formed in the flange whereby to prevent relative movement of the flier wire support with respect to the flier body and means to lock the complementary members together.

13. A flier for spinning machines and the like comprising, a centrally apertured body member having base and head portions, a peripheral flange formed on the body portion between the base and head portions, said flange having slots cut therein at diametrically opposite points, a peripheral flier wire support receiving groove formed in the body above said flange, a flier wire support comprising two complementary members,

each having a body portion formed with a recess defining arms in the vicinity of the open end of the recess and a prong member formed by striking out a portion of the body adjacent the recess, the opposite arms of the respective members being adapted to overlap when the recessed portions thereof are seated in the peripheral groove, said prong members seating in the slots formed in the flange whereby to prevent relative movement of the flier wire support with respect to the flier body, the end of each of the body portions opposite the recess being turned backwardly upon itself to form a slot adapted to receive a flier wire and means to lock the complementary members together.

14. A flier for spinning machines and the like comprising, a centrally apertured body member having base and head portions, a peripheral flier wire support receiving groove formed in the body member between the base and head portions, a flier wire support adapted to seat in said groove comprising complementary members having recessed body portions defining arms in the vicinity of the open end of the recessed portions, the opposite arms of the respective complementary members being adapted to overlap when the recessed portions thereof are seated in the peripheral groove, means formed on said complementary members adapted to receive the arms of the flier wires, a flier wire having a central block engaging section and arms extending outwardly therefrom mounted upon the block, the arms of the wires overlapping in the vicinity of the block, the portions of the arms therebeyond being in engagement with the wire retaining means and means to securely lock the complementary members together.

15. A flier for spinning machines and the like comprising, a centrally apertured body member having base and head portions, a peripheral flange formed on the body portion between the base and head portions, a peripheral flier wire support receiving groove formed in the body above said flange, a flier wire support comprising complementary members having recessed body portions defining arms in the vicinity of the open end of the recessed portions, the opposite arms of the respective members being adapted to overlap when the recessed portions thereof are seated in the peripheral groove, means formed on one of the complementary members adapted for engagement with the peripheral flange whereby to prevent relative movement of the flier wire support with respect to the flier body, means formed on said support for attaching flier wires thereto, a flier wire having a central block engaging section and arms extending outwardly therefrom mounted upon the block, the arms of the wires overlapping in the vicinity of the block, the portions of the arms therebeyond being in engagement with the wire retaining means and means to lock the complementary members together.

MICHAEL J. McHALE.
